UNITED STATES PATENT OFFICE.

EDWARD MERRITT, OF BROCKTON, MASSACHUSETTS.

NAIL-DRIVING MACHINE.

SPECIFICATION forming part of Letters Patent No. 278,252, dated May 22, 1883.

Application filed September 8, 1882. (No model.)

To all whom it may concern:

Be it known that I, EDWARD MERRITT, a citizen of the United States, residing at Brockton, in the county of Plymouth and State of Massachusetts, have invented certain new and useful Improvements in Nail-Driving Machines; and I do hereby declare that the same are fully described in the following specification and illustrated in the accompanying drawings.

My invention relates to improvements in nail-driving machines; and it has for its objects the provision of means to produce a constant though varying pressure of the work against the throat or the presser-foot of the machine, and to provide means for clinching the nails in work having curved or irregular surfaces.

The invention is carried out as follows, reference being had to the accompanying drawings, where—

Figure 1 is a side elevation, partly in section, of a nailing-machine embodying my invention. Fig. 2 is a front elevation. Fig. 3 is a plan view of the upper end of the horn; and Fig. 4 is a vertical section of the horn, clinching-cup, nail-throat, and a piece of work.

Like letters refer to like parts in all the figures.

30 A represents the fixed head of the machine, provided with the vertically-operated presser-foot B and nail-feeding mechanism C. The swinging head D, in which the awl E and driver F are alternately operated, is pivotally supported by a standard, A', on the fixed head A. In the fixed head A, as shown by dotted lines, Fig. 1, is journaled a rock-shaft, A², one arm, A³, of which is provided with a friction-roller, which rides in the groove of a cam, A⁴, 35 on the main shaft G, and the other arm of which, being slotted, is connected to the swinging head D by a sliding block on a bolt or stud, a, secured by a thumb-nut in a slot in the face of the swinging head D, by which means the 40 point of connection of said arm and head may be adjustably fixed nearer to or farther from the axial line of the rock-shaft A² and the length of the oscillation or extent of the swinging movement of the head D regulated. To 45 the swinging head D is attached a rigid throat, H, which therefore partakes of the movements of the head D.

I represents the horn, which at its upper end is provided with a clinching-cup, J, having a central depending lug, j. The cup J is 55 adapted by the concavity of its upper surface to turn the point of a nail coming in contact therewith upward into the material through which it is driven, and by the convexity of the bearing-surface of the cup, in connection 60 with the concave recess i of the horn I, it automatically adjusts itself to uneven, irregular, or curved surfaces pressed thereon or thereby, and thus presents its clinching-face in such position to the driven nail as to clinch the 65 same without regard to the general position of the cup as a whole. To retain the movements of the cup within certain limits, the lug j is directed within an aperture, i', in the bottom of the recess i, which being larger than 70 the lug, only a limited movement of the lug in said aperture can occur. The lower end of the horn I is pivotally secured to one end of a T-lever, K, and the weight of the horn is overbalanced by a weight, L, adjustably secured 75 to the opposite end of said lever, while the third branch thereof is pivotally secured to a bracket, M', formed on the standard M of the machine, said pivotal attachment being at m, or as nearly on a level with the bottom of the 80 throat H as practicable. In the bracket M', outside of the pivot m, a second lever, N, is pivoted, and its upper end is curved to bear against the face of a cam, N', fixed to the end of the main shaft G, and it has a depression, 85 n, on its face. The lower end of the lever N is provided with a spring, O, comprising two or more leaves adjustably secured upon each other by the bolts o o, passing through slots 90 therein, whereby the outer leaf or leaves may 95 be moved upon the inner from or toward its end, so as to increase or diminish the stiffness of the spring as a whole, and its lower end being seated in an aperture, k, in the lever K, back of its pivot, the pressure of the spring 100 against the lever may be regulated as to its quantity, while its constancy is maintained by the upper end of the lever N bearing against the face of the cam N' during all the operations of the machine, except the feeding of the material, when the upper end of said lever is in the depression n on the cam N'. An additional spring, P, is provided to cause the upper end of the lever to ride in the depression

n. A bracket, N², is formed on the front of the standard M, and slotted to act as a guide for the lever K, and a treadle, Q, and rod R are provided for the purpose of withdrawing the front end of the lever and the horn I, supported thereon, from the throat H, to allow the work to be placed on the horn.

This being the construction, the operation is as follows: After the work has been placed on the horn I the pressure on the treadle Q is released and the horn rises by the action of the weight L and spring O until the work is pressed against the throat H. If you now start the machine, the presser-foot B is forced down by the action of its cam, (not shown in the drawings,) which is on the main shaft G, causing the work and horn to be forced away from the throat against the action of the weight and spring. The function of said presser-foot B is to press the work and horn away from the throat H to allow the latter and its swinging head D to swing back the distance required for the feed between the nails. The driver F now begins to rise and the swinging head D begins its backward stroke. When the head has reached the extent of its backward stroke the presser-foot rises and allows the work and the horn I to be forced upward against the throat H, and the awl E descends and enters the work. Now the upper end of the lever N enters the depression n on the cam N', thereby wholly releasing the pressure of the spring O on the horn, leaving the weight L to press the horn upward to such an extent only as not to interfere with the feeding of the work over the end of the horn by the forward stroke of the swinging head D, with its awl E in the work, which now ensues. When the head D has reached the limit of its forward stroke the increased pressure of the spring O on the horn I is now caused by the action of the cam N' on the upper end of the lever N to force and hold the work against the throat H while the awl E is being withdrawn from the work, and the nail enters the perforation made by the awl and is being driven by the driver F. This operation is repeated until the whole of the shoe-sole or work has been nailed, after which the horn I is withdrawn and another shoe or piece of work placed on the horn, ready for nailing.

Having thus fully described my invention, what I claim is—

1. In a nail-driving machine, a counterbalanced suspended horn, in combination with a rigid throat and vertically-operating presser-foot, substantially as shown and described.
2. A counterbalanced suspended horn, combined with a rigid throat and a vertically-operating presser-foot, and with means, substan-

tially as described, for sustaining a constant and varying pressure of the horn against the same, substantially as and for the purpose set forth.

3. A counterbalanced suspended horn, combined with a vertically-operating presser-foot, and a swinging head provided with a rigid throat, substantially as and for the purpose set forth. 65

4. The combination of a swinging head provided with a rigid throat, a driver and an awl, and a horn having a concave seat, and a clinching-cup having a convex outer bearing-surface, adapted to rest in the concave seat and to automatically adjust itself to the surface of 75 the work, substantially as described.

5. The combination of a horn having a concave seat and a clinching-cup having a convex outer bearing-surface adapted to rest in the concave seat, substantially as described. 80

6. The combination of a horn having a perforated concave seat and a clinching-cup having a convex outer bearing-surface and a central depending lug smaller than the perforations in the seat, substantially as shown and 85 described.

7. The combination of a suspended T-lever, a horn pivoted to one arm thereof, a weight adjustably secured to the opposite arm thereof, and a spring arranged in rear of the point of 90 suspension, and means, substantially as described, for intermittently removing the pressure of said spring, substantially as shown and described.

8. In a nailing-machine, the combination of 95 the rigid throat H, the revolving horn I, arranged upon the suspended lever K, the adjustable counter-balance L on said lever K, the variable spring O, and the treadle Q, connected to lever K, as and for the purpose set forth. 100

9. In a nailing-machine, the combination, with the main shaft, of an end cam provided with a recess, a lever sliding thereon and adapted to variably press a horn against a presser-foot or throat, and an intermediate cam 105 adapted, through the medium of a rock-shaft, to oscillate a swinging head provided with said throat, substantially as shown and described.

10. The combination of the end cam, the lever provided with an adjustable spring, and the suspended horn, substantially as shown and described. 110

In testimony whereof I have affixed my signature in presence of two witnesses.

EDWARD MERRITT.
